US00D949950S

(12) **United States Design Patent** (10) **Patent No.:** **US D949,950 S**
(45) **Date of Patent:** **** Apr. 26, 2022**

(54) **PROJECTOR**

(71) Applicant: **SHENZHEN LIGHT VALVE TECHNOLOGY CO., LTD**, Shenzhen (CN)

(72) Inventor: **Jiaoxian Wei**, Hengyang (CN)

(73) Assignee: **SHENZHEN LIGHT VALVE TECHNOLOGY CO., LTD**, Shenzhen (CN)

(**) Term: **15 Years**

(21) Appl. No.: **29/784,757**

(22) Filed: **May 21, 2021**

(51) **LOC (13) Cl.** **16-02**

(52) **U.S. Cl.**

USPC **D16/230**

(58) **Field of Classification Search**

USPC D16/221, 225, 230-231, 234; D21/514
CPC G03B 21/145; G03B 21/16; G03B 21/00;
G03B 21/003; G03B 21/12; G03B 21/14

See application file for complete search history.

(57) **CLAIM**

The ornamental design for a projector, as shown and described.

DESCRIPTION

FIG. 1 is a perspective view of a projector showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the projector;

FIG. 10 is an enlarged view of portion 10 shown in FIG. 4;

FIG. 11 is an enlarged view of portion 11 shown in FIG. 5;

and,

FIG. 12 is an enlarged view of portion 12 shown in FIG. 8.

The broken lines in the drawings depict portions of the projector that form no part of the claimed design.
